PUMPING UNIT FOR WELLS

George T. Humphrey, Dallas, Tex., assignor to Republic Supply Company, Houston, Tex.

Application January 13, 1937, Serial No. 120,418
Renewed March 6, 1939

7 Claims. (Cl. 74—103)

This invention relates to well pumping equipment and it has particular reference to a suspension bearing and straight lift unit for well pumping units.

The principal object of the invention is to provide a device whose construction is such that it will be applicable to three distinct uses on a pumping unit, namely; to afford a suspension for a walking beam to enable the latter to be displaced longitudinally during reciprocation; to afford a pivotal connection between the beam and pitman arms at its power end and to provide for a two point pivotal connection between the operative end of the beam and the polished rod.

Another object of the invention is to provide a medium by which the walking beam is constrained to follow a predetermined path, i. e., perpendicular, at its operative end to maintain alignment of the polished rod through the stuffing box; to prevent undue wear thereon in operation.

Broadly, the invention aims to provide a walking beam capable of self alignment with the polished rod and a suspension in which the pivotal point of the beam may be spaced from the actual point of suspension thereof, thus to provide for longitudinal displacement of the beam in operation, which fact will enable the polished rod to follow a perpendicular path without restraint, to reduce frictional wear thereon and on the stuffing box packing surrounding the same.

Moreover, the invention contributes to the economy of construction and operation of a well pumping unit inasmuch as the heretofore independently fabricated elements of a unit are made interchangeable and inexpensively replaceable.

With the foregoing objects as paramount, the invention has other and lesser objects, as well as certain salient features of construction and operation of parts to become manifest as the description proceeds, taken in connection with the accompanying drawings, wherein:

Figure 1 is a perspective view of a pumping unit constructed according to the present invention.

Figure 2 is a front or rear elevation of the suspension bearing of the invention, showing its use as a pitman connection to a walking beam.

Figure 3 is a side elevation of the suspension bearing.

Figure 4 is a side elevation of the suspension bearing in vertical section on lines 4—4 on Figure 2.

Figure 5 is a front or rear view of the suspension bearing, in vertical section, showing its adaptation as a beam supporting means.

Figure 6 is a plan view of the crown plate of the Samson post, slotted to receive the suspension arms of the bearing, in support of the walking beam.

Figure 7 is a fragmentary side elevation of the beam control means and

Figure 8 is a plan view on lines 7—7 on Figure 8.

Continuing with a more detailed description of the drawings, reference is primarily made to Figure 1 in which is shown a pumping unit constructed according to the present invention in the sense that its walking beam 1 is suspended in the Samson post 2 by a bearing embodying the invention; that the pitman arms 3 are similarly connected to the beam and further, that the rod hanger at the forward end of the beam is connected thereto through the same medium. Accordingly, it is apparent that not only is the beam 1 itself mounted in the Samson post by a device embodying the invention, but also its appurtenances, such as the rod hanger and pitman as well as the means by which it is constrained to follow a predetermined path in its travel. It is also pointed out that these connections or bearings, being of similar construction and size are interchangeable and independently replaceable.

The Samson post 2, in the present case, consists of four I-beams, having their lower ends mounted on a concrete base 4 with their upper ends converging. The upper ends are wholly embraced by a series of plates 5, with a crown plate 6 superimposing the same. This plate is shown in plan view in Figure 6.

Upon the plate 6 is disposed a short section of I-beam 7 and upon this I-beam, in turn, is welded a box 8. At this point, attention is directed to the fact that in all of the three uses to which the invention is adapted, the construction of the invention per se does not vary. Since this is true, the same characters of reference will be employed throughout the several views in the drawings to denote similar parts.

Continuing with the beam suspension, it will be noted that the box 8 receives a cast block or bearing 9, as shown in Figures 4 and 5, which has a concave recess or trough a therein to receive the roller or cylindrical member 10 whose surface conforms with the concave of the recess a.

A block b is welded to the roller 10 at a point on its surface, parallel to the longitudinal axis of the roller and to either end of this block is affixed by welding or other suitable means, an arm 11. In the case of the walking beam 55

hanger, these arms depend through slots *c* in the crown plate *6* (Fig. 6) and pivotally engage the stub shaft of a bearing *12* (Fig. 1) on either side of the walking beam *1*. It is to be noted that the bearing *12* is affixed to the underside of the walking beam at a point midway between the ends of the latter.

Thus, it will be seen that as the beam *1* is rocked, the roller *10*, oscillates in its recess *a* in the bearing *9*. The beam *1*, being suspended in the manner described, is capable of longitudinal displacement with minimum friction at its point of suspension and may therefore follow the perpendicular travel of the polished rod, (not shown) rather than forcing the latter to follow an arcuate path in its reciprocation, which is objectionable inasmuch as wear occurs on the rod and its packing, requiring that it be repaired or replaced at frequent intervals.

In the case of the application of the invention as a means of connection between the pitman arms *3* and the beam *1*, a cross-head *13*, in the form of a pair of parallel bars, is provided, whose ends are reinforced to receive the ends of the pitman arms *3* as shown in Figure 1. The lower ends of the arms *11* of the suspension bearing embrace a bearing block *14* (Fig. 2) which is apertured to receive a pivotal pin *15* (Fig. 1). The cross-head *13* is therefore capable of rocking motion, if such is necessary, to compensate for any variation in the throw of the cranks *16* of the power unit *17* or other measurements, without affecting the operation of the walking beam *1*.

The foregoing is likewise true of the application of the invention as a connection between the walking beam *1* and the well rods through the polished rod. A connection similar to the cross-head *13* is recommended for the joining of the operative end of the walking beam to the polished rod (not shown). Such a connection will lend the desired freedom of movement to the polished rod and this, combined with the yielding tendency of the walking beam, due to its form of suspension described, will add materially to the period of usefulness of the polished rod, as well as aiding the productiveness of the pumping equipment in the well.

The invention is especially valuable from the standpoint of effectiveness as well as economy and to prevent its deterioration by wear of the elements, the box *8* is filled with a lubricating medium. A hood or cover *16a* protects the bearing against ingress of moisture, dust and the like and is welded or otherwise affixed to the bar *b*, secured to the roller *10* in the box *8*, as shown.

With the foregoing provisions, it is obviously necessary to provide means for holding the walking beam against undue movement, since the same is swung freely from a point above the center of its major axis. This provision consists primarily of a gear or sprocket *17a*, two of which are provided, one on either side of the bearing *12*, which supports the walking beam *1* midway between its ends and a shaft *18*, through the bearing. The shaft joins the two sprockets *17a* and this shaft is in fixed relation with the walking beam *1* in order that the rotation of the sprockets is in proportion to the degree of displacement of the arms *11* and the walking beam *1*, effected by the pitmans *3*, in one direction and the downward pull of the well rods in the opposite direction.

It will be observed that the lower ends of the arms *11* in Figure 7 are displaced relative to a

vertical line through the head of the Samson post, in the direction of the operative end of the walking beam *1*. It is obvious therefore that due to the displacement of the beam, its tendency will be to yield to the weight *19* on its rearward end on its upward stroke.

In order, however, to insure control of the operative end of the beam, both in its upward and downward stroke, the sprockets *17a* are each surrounded by chains *19*, the ends of each being secured in the manner shown in Figure 7, to one of the legs *2* of the Samson post. A bolt *20* is passed through the chains and sprockets at one point or at a point diametrically opposite the point of securement of the chain ends when the beam *1* is in horizontal position. This will hold the suspension arms *11* of the beam always at an angle relative to the vertical plane and one lead of each chain *19* will always be taut or under tension.

When the beam *1* is actuated, the chains will constrain the beam to swing toward the well rods at each extreme position but since the center of gravity of the beam is held in displaced position by the chains, its weight alone will urge the beam longitudinally away from the rods as it passes a point midway between its extreme points of displacement. Hence the effect of maintaining the operative end of the beam on a straight perpendicular line, which prevents undue wear on the rods and packing.

Manifestly, the construction as shown and described is capable of some modification and such modification as may be construed within the scope and meaning of the appended claims is also considered to be within the spirit and intent of the invention.

What is claimed is:

1. A well pumping unit including a walking beam, a suspension bearing comprising a base portion, a box superimposed upon said base portion, a bearing block enclosed by said box, a cylindrical bearing mounted upon said block and having a second block fixedly mounted thereto, depending suspension arms affixed to said latter block, means holding said suspension arms at an angle relative to the vertical plane, said means also causing said walking beam to be progressively moved longitudinally as it approaches its extreme positions of displacement in operation. 50

2. In a well pumping unit, a walking beam, a box mounted upon said walking beam, a bearing enclosed by said box, a cylindrical member reciprocably mounted upon said bearing, a second block mounted upon said cylindrical member, and arms affixed to said latter block to support said walking beam. 55

3. In a well pumping unit, a walking beam, a substantially rectangular box mounted upon said walking beam, a bearing enclosed by said box, a cylindrical member reciprocably mounted upon said bearing, and arms rigidly attached to said cylindrical member at a point spaced from the axis thereof to support said walking beam for longitudinal displacement. 60

4. In a well pumping unit, a walking beam, a bearing attached to said walking beam, a cylindrical member reciprocably mounted upon said bearing, and arms attached to said cylindrical member at a point spaced from the axis thereof to support said walking beam at a point below its major axis for longitudinal displacement, and means to control the longitudinal displacement of said beam. 70

5. A well pumping unit including a walking 75

beam suspended from a point above its major axis, a suspension bearing comprising a box, a removable bearing in said box, a rotatable member conformably received in said bearing, a pair 5 of parallel suspension arms operatively connected to and depending from said rotatable member and supporting said beam, means constraining said arms to lie at an angle to the vertical, said means also causing said walking beam to be progressively displaced longitudinally during its 10 reciprocation past its horizontal plane.

6. A well pumping unit including a supporting post and a suspension bearing mounted thereon, said bearing comprising a box mounted on said post, a removable, recessed block therein, rotatable means conforming to the recess in said

block, suspension arms connected to and depending from said rotatable means and supporting said beam intermediate its ends, means holding said arms at an angle relative to the vertical plane, said means also imparting a forward thrust to said beam on either side of its horizontal plane. 5

7. A well pumping unit including a supporting post, a walking beam, means suspending said beam from said post at a point below its major axis and intermediate its ends, means constraining said suspending means to lie at an angle relative to the vertical plane, said means also constraining said beam to progressively move longitudinally as it passes the horizontal plane during reciprocation. 10
